UNITED STATES PATENT OFFICE.

ALMON W. CURTIS, OF CORTLAND, NEW YORK.

SPRING-BAR FOR VEHICLES.

1,160,858.

Specification of Letters Patent. Patented Nov. 16, 1915.

Application filed March 28, 1913. Serial No. 757,346.

To all whom it may concern:

Be it known that I, ALMON W. CURTIS, of Cortland, in the county of Cortland, in the State of New York, have invented new 5 and useful Improvements in Spring-Bars for Vehicles, of which the following, taken in connection with the accompanying drawings, is a full, clear, and exact description.

This invention relates to certain improvements in spring bars for vehicles, adapted 10 to be mounted upon the upper half of an elliptical spring for receiving the body supporting brackets and thereby supporting the body of the vehicle. Heretofore, so far as 15 I am aware, these bars have always been made of wood, such as hickory, iron-wood, or its equivalent, having closely knit tenacious fiber, but owing to the increasing scarcity of this class of wood and the fact that 20 inferior grades of wood will not serve the purpose without increasing the size or bulk and thereby destroying the delicate symmetry and graceful lines which the trade demands, I have sought to provide a metallic 25 substitute which will be more effective than the best grades of wood and may be made upon the same external lines as the original wood bars.

In other words, the main object is to provide 30 an all metal, one-piece spring bar which is light, strong and durable and capable of being made to present the same external appearance as any of the usual wood bars now employed.

Another object is to provide the ends of 35 the bar with means whereby the body supporting brackets may be adjustably secured thereto for different widths of bodies.

A further object is to make the bar substantially U-shaped in cross section so as to 40 form a lengthwise channel and opposite reinforcing ribs for receiving and concealing the nuts or bolt heads which may be employed in securing the body brackets and 45 spring to the bar, the reinforcing ribs also serving to hold the nuts or bolts against turning.

Other objects and uses relating to specific 50 parts of the bar will be brought out in the following description.

In the drawings: Figure 1 is a front elevation of an elliptical spring and my improved cross bar mounted thereon, portions 55 of the body brackets being also shown in operative position. Figs. 2 and 3 are, respectively, an enlarged top plan and an in-

verted plan of the cross bar shown in Fig. 1. Fig. 4 is a longitudinal sectional view of the same bar. Figs. 5, 6 and 7 are enlarged transverse sectional views, taken respectively on lines 5—5, 6—6 and 7—7, Fig. 1.

In order that my invention may be clearly understood, I have shown an elliptical spring 1— as mounted upon an underlying axle or other support 2— for receiving and supporting a cross bar 3— by which the body (not shown) of the vehicle is supported, through the medium of body brackets 4—. The bar 3— preferably consists of a single piece of wrought steel, U-shaped 70 in cross section and forged, pressed or rolled to the desired form to produce a lengthwise channel 5— and opposite lengthwise reinforcing ribs 6— running practically the entire length of the bar, except that suitable cross ribs are provided at predetermined intervals for purposes hereinafter described.

The upper portion of the main body of the bar is oval or convexed in cross section except at the extreme ends, which are ornamented with suitable scrolls 7— to give the bar a more graceful and pleasing appearance, corresponding to the end scrolls of the usual wood bars. The upper side of the bar is disposed in a substantially straight, horizontal line, longitudinally, the central portion of said bar being of greater vertical depth than the remaining portions of its ends, and of a width substantially equal to that of the adjacent portion of the spring to which it is secured and its lower side is concaved longitudinally, at 3', to conform to the curvature of the spring upon which it is seated, while the ends of the bar are tapered from the enlarged central portion 95 toward their extremities.

As shown more clearly in Figs. 2 and 4, the upper faces and portions of the sides of the central portion of the bar are provided with transverse grooves or recesses 8— spaced equi-distant apart from the center of the bar for receiving clips 9—, by which the bar is secured to the upper side of the spring, as shown in Figs. 1 and 6, said recesses and clips being of substantially the same width lengthwise of the bar to hold the clips and bar against relative endwise movement and at the same time allowing the upper portions and sides of the clips to be brought into closer coincidence with the corresponding faces of the bar, to relieve such bar, as far as possible,

from abrupt projections when assembled upon the spring. As previously stated, the lengthwise ribs —6— running along the opposite longitudinal edges of the bar are spaced a distance apart, corresponding approximately to the width of the spring, but are connected at predetermined intervals by transverse ribs or webs —10—, —11— and —12—, the rib —10— being located midway between the ends of the bar and having its lower edge substantially coincident with the center of the arch of the concave seat 3', so as to form a central bearing on the spring, and is provided in its under side with a recess —13— for receiving the head of a bolt —14—, by which the leaves of the upper portion of the spring are secured to each other. The transverse ribs or webs —11— are located equi-distant from and at opposite sides of the center rib —10— at the ends of the concave seat 3', so as to form additional bearings for the spring, the lower edges of said ribs —11— being substantially coincident with the plane of the ends of the concave seat. The ribs or webs —12— are located at the termini of the bar but their lower edges are substantially coincident with the adjacent lower edges of the ribs —6— and are provided with recesses —15— forming a part of the ornamental scroll —7—. It is now clear that aside from the transverse grooves or recesses —8— and scrolls —7—, the external surface of the bar is substantially smooth and unbroken, while the transverse ribs —10—, —11— and —12— lie wholly within and above the lower edges of the adjacent portions of a lengthwise rib —6— and are, therefore, concealed from view, the ribs —11— being located at the ends of the concave seat, while the rib —10— is located midway between the ribs —11—. This bar is adapted to be used for supporting bodies

of different widths and in order that the brackets —4— may be adjusted relatively 45 to the bar to conform to such different widths of body, the ends of said bar are provided with a series of apertures —16— arranged uniform distances from the center and, in sequence, from the ends of the bar, 50 for receiving clamping bolts, as —17—, by which the upper ends of the brackets —4— are firmly secured to said bar. These apertures —16— are disposed vertically and centrally through the upper curved side of 55 the bar in alignment with the longitudinal center of the channel —5—, so as to enable the nuts of the bolts to enter said channels and engage the ribs thereof, as shown more clearly in Fig. 7, thereby upholding the 60 nuts against turning while the bolts are being tightened or loosened, the ribs serving to conceal the nuts from view when placed in operative position.

What I claim is:

A one-piece metal spring-bar having its upper face rounded in cross-section and its underside channeled longitudinally to form opposite lengthwise ribs, said bar having vertical apertures near its ends and its remaining portion imperforate and provided with transverse ribs at opposite sides of and equi-distant from the center, the lower side of the bar having a concave seat terminating at the transverse ribs, and a central cross rib midway between said transverse ribs, the upper side of the bar being provided with transverse recesses between the transverse ribs and central cross rib. 75

In witness whereof I have hereunto set 80 my hand this 26th day of March, 1913.

ALMON W. CURTIS.
